COMPRESSION UNIT

Philip A. Celander, Bloomington, Ill., assignor to
 Williams Oil-O-Matic Heating Corporation,
 Bloomington, Ill., a corporation of Illinois

Application April 25, 1934, Serial No. 722,294

1 Claim. (Cl. 230—56)

This invention relates to improvements in refrigeration and more particularly to a refrigeration machine of the compressor type combined with an internal combustion engine for operating the compressor.

Commercial refrigeration machines of the compression type in which the compressor is operated by an electric motor have been marketed for some time. Such units depend upon the availability of commercial electric power such as employed in commercial lighting systems found in all communities of over a certain population and are not available to the farmer, rancher, miner or others living in sparsely populated areas and at a distance from a source of commercial electricity.

In order to provide a refrigeration unit independent of commercial electricity or a source of power, an internal combustion engine is combined in the unit to provide the necessary power. It is one of the objects of this invention to provide such a unit with means allowing the cranking of the internal combustion engine independently of the compressor and after the engine is operating to connect a driving pulley thereof to a driving pulley of the compressor to operate the refrigeration device.

With the wide use of the internal combustion engine and the wide distribution of fuel therefor, the advantages of such a refrigeration unit are obvious.

With these and other objects in view, reference is made to the accompanying sheet of drawings which illustrates a preferred form of this invention with the understanding that minor changes may be made without departing from the scope thereof.

In the drawing:

Figure 1 is a view partly in elevation and partly in vertical section of a refrigeration unit constructed in accordance with this invention.

Figure 2 is an enlarged detail view in section taken on the line 2—2, Figure 1, with the internal combustion engine removed.

Figure 3 is a view in section taken on the line 3—3, Figure 2, looking in the direction of the arrows.

A compressor C of a commercial refrigeration machine and a commercial internal combustion engine E are mounted upon a base 1 supported on legs 2. The compressor C is immovably mounted upon one end of the base 1 and is provided with a driving pulley 3 mounted upon an exterior end of the crank shaft, not shown, of the compressor. The internal combustion engine E is secured upon a base 4 mounted to reciprocate upon a track 5 upon the other end of the base 1 and is provided with a driving pulley 6 upon the same side as the compressor

pulley. A pulley belt 7 is arranged to operatively connect the pulleys 3 and 6. A crank 8 is provided upon an exterior projection of the engine crank shaft opposite the pulley 6 for initiating operation of the engine.

The engine E is mounted upon base 4 in any desired manner, such as being clamped upon the pads 9 thereon. The base 4 is mounted to travel upon the oppositely disposed tracks 5 upon the base 1, and is normally extended to the outer limit thereof by the coil springs 10 having ends anchored upon the base 1 and the other ends in engagement with brackets 11 upon the under side of the reciprocating base 4 of the engine E. These springs are of sufficient strength to normally maintain an operating tension upon the power belt 7.

In order to disconnect or reduce the tension of the belt 7 to allow the cranking of the internal combustion engine E independently of the compressor C, a cam 12 is mounted upon a bracket 13 positioned in front of the base 4 when in normal position. It is preferable to adjustably secure the bracket 13 by studs 14 threaded into mounting blocks 15 secured to the interior of the base 1, as shown in Figure 1. The cam 12 includes a circular portion mounted eccentrically upon a pivot 16 upon the bracket 13 and is provided with an operating handle 17. The cam 12 is mounted in the axis of the reciprocable base 4 and when in this position, shown in full lines in Figure 2, will be out of contact therewith. Upon rotation of the handle, as shown in dotted lines in said figure, the cam surface will engage the outer end of the base 4 and move it in the direction of the compressor C against the tension of the springs 10. The movement of the base 4 carries the engine E and engine pulley 6 in the direction of the compressor, releasing the tension on the belt 7, as shown in dotted lines in Figure 1.

What I claim is:

The combination with a compressor mounted upon a base of an internal combustion engine mounted to travel to and from the compressor upon the same base having a belt drive for the compressor, coil springs between the compressor and engine anchored at the ends adjacent the compressor to the base and pressing upon the engine to maintain the belt tight, an adjustable bracket mounted on the engine end of the base and extending therebeyond, and a handle terminating in a flat circular end eccentrically pivoted upon the bracket to cause the cam surface thereof to engage the engine and upon rotation of the handle to move the engine to compress the springs and loosen the belt to lessen the load in starting the engine.

PHILIP A. CELANDER.
